Attorney.

UNITED STATES PATENT OFFICE.

JOHN WILSON ORROCK, OF MONTREAL, QUEBEC, CANADA.

METAL DOOR.

Application filed November 26, 1920. Serial No. 426,631.

To all whom it may concern:

Be it known that I, JOHN WILSON ORROCK, a subject of the King of Great Britain, and resident of the city of Montreal, in the Province of Quebec and Dominion of Canada, civil engineer, have invented certain new and useful Improvements in Metal Doors; and I do hereby declare that the following is a full, clear, and exact description thereof.

My invention relates particularly to doors for wharf sheds and the like and has for its object to provide an all metal door of relatively light weight and possessing strength and durability and the advantageous feature of simplicity of construction. The invention consists of a frame and panels constructed and assembled to afford mutual reinforcement and, preferably, to provide a frame for a window sash. The essentials constituting the subject matter of my invention being radial corner integral projections from the frame, the ends of which, because of their radial nature extend beyond the main length and breadth of the frame proper, at each side and top and bottom thereof, thus reducing the span between the frame members, spaced bracing means being located transversely to the frame and connecting the vertical members; while hangers for the door are rigidly secured to the radial projections at the top corners and in alignment with the vertical side members. This frame has metal sheeting covering the same and extending laterally and upwardly and downwardly to points slightly beyond the end of the radial corner projections.

For full comprehension, however, of my invention reference must be had to the accompanying drawings in which similar reference characters indicate the same parts and wherein:

Figure 1 is a front elevation of a door constructed according to my invention;

Figure 2 is a vertical sectional view taken on line 2—2 Figure 1;

Figure 3 is a transverse sectional view taken on line 3—3 Figure 1;

Figure 4 is a detail view of one of the radial extensions drawn to a larger scale with horizontal edge;

Figure 5 is a transverse sectional view taken on line 5—5 Figure 4;

Figure 6 is an edge elevation of the radial extension;

Figures 7, 8, 9 and 10 are detail views of parts of the hangers;

Figure 11 is a front elevation of a modified form of the door;

Figure 12 is a vertical sectional view taken on line 12—12 Figure 11;

Figure 13 is a horizontal sectional view taken on line 13—13 Figure 11; and

Figure 14 is a sectional view taken on line 14—14 Figure 11.

In Figures 1, 2 and 3 I have illustrated a high door such as is necessary for communication between a wharf shed and a steamship and in Figures 11, 12 and 13 a door through which communication is effected between the shed and railway cars on a siding.

The frame I have illustrated forms a part of the subject-matter of an application for patent filed by me under No. 353,664 on January 24, 1920, and consists of vertical side frame members 2 and 3 respectively and horizontal top and bottom members 5 and 6 respectively, the abutting ends of these members being bent outwardly as at 4 relatively to the frame at an angle of 45° to the frame members thus causing the abutting bent ends to coincide and form a radial corner extension, the ends of which form the corners of a rectangular figure longer and wider than the frame proper. These frame members preferably consist of angle irons and the contacting flanges 9 of the radial corner extensions are fastened together by rivets or bolts 10. The frame thus formed is braced or stiffened by transverse members 7 and 8.

According to my present invention I adapt this frame to a sheet metal door by combining therewith the essential elements thereof and the particular arrangement necessary to impart to the door self-sustaining properties. To this end I secure to the top radial corner extensions and in alignment with the side frame members 2 and 3, right and left hand hangers secured rigidly to and enveloping the full cross section of these corner extensions within the width of the hangers, which being in alignment with the side frame members as above mentioned, and em-

bracing both ends of the top frame member, absorb the entire load which effect is contributed to by the reduction in span due to the narrow skeleton frame relatively to the 5 full width of the door presented when the filling or sheeting is in place.

These hangers consist of front and back members for each hanger, right and left front hangers and right and left back hangers being necessary. In order to provide even and corresponding front and back faces for the radial extensions each is supplemented by back faces presented by comparatively short angle irons. These short angle 10 irons are of sufficient length to receive the rivets or bolts 10 for fastening together the bent ends 9 of the frame piece. They are indicated at 15 Figure 5 where it will be seen that corresponding bearing faces are 20 presented at both front and back of the door. The hangers proper consist of right and left front members 20 and corresponding right and left back members 22. Each of these members consists of a plate with one end 25 bent at right angles as at 25 to form, when assembled with their ends 25 overlapping, a reinforced suspension member, the main length of which is secured to the radial extensions of the skeleton frame by bolts 30 30 securely fastening the front and back members to the flanges presented by the members 9 and 15; the members of the hangers and the members 9 and 15 being provided with bolt holes for the purpose. These overlapping 35 portions have registering holes 26 in which the hanger-bolt 27 is pivotally connected. This hanger-bolt is a part of the usual trolley frame 28 hung from the trolley wheel 29 travelling in a rail 60 shown 40 clearly in Figures 1, 2, 11, 12 and 14. The skeleton frame thus constructed and hung is reinforced at its bottom by a plate 35 extending throughout the full width of the door.

45 The body of my improved door is presented by sheets 40 of metal, preferably corrugated galvanized iron, laid-in panels and riveted together and to the skeleton frame as indicated in Figures 1 and 11. The tall 50 door, for steamship service, illustrated in Figures 11, 12 and 13 has an upper portion as compared with the shorter door for railway service illustrated in Figures 1, 2 and 3 and this upward extension has separate 55 shorter sheets 41. In order to accommodate a window sash, vertical window frame pieces are formed by vertical angle irons 42 fastened at their top and bottom ends to the frame members 5 and 7.

60 The shorter sheets 41 are riveted at their inner side edges to the frame bars formed by the angle irons 42 and their outer side edges extend outwardly to present straight side edges with the outer edges of the sheets 65 40. These edges form the side margins of

the complete door and extend in width slightly beyond the radial extensions, these side edges being bent back upon themselves as shown at 43 in Figure 3. The top of the door is completed by short pieces 45 of sheeting, riveted at their lower edges to the top frame piece 5 and at their opposite side edges as at 46 to the sheets 41 while their inner edges are overlapped and riveted together as at 47. The frame thus produced 70 may have a steel sash 50 with wire glass, set therein.

As shown in Figures 1 and 11 a door constructed according to my invention may be hung from the overhead rail 60 with minimum strain coming upon the filling or sheeting. It is of relatively light weight and possesses strength and durability with simplicity of construction; while the manner of connecting the hangers permits of their 80 width and consequently the strength of connection being extended to meet larger and heavier doors or narrowed to suspend doors of lighter weight.

What I claim is as follows:

1. A door for the purpose set forth consisting of a metal frame presenting radial corner projections projecting beyond the remaining metal component of the door; spaced transverse bracing means connecting the vertical members; hangers rigidly secured to the top corner projections in alignment with the side frame members and metal body members producing a door area overlapping the said corner projections to 100 the extreme ends of the latter for the purpose of eliminating splitting action along the side edges.

2. A door for the purpose set forth consisting of a metal frame presenting radial corner projections; spaced transverse bracing means connecting the vertical members; hangers rigidly secured to the top corner radial projections in alignment with the side frame members and having their lower edges rigidly secured along the frame and metal body members producing a door area overlapping the said corner projections to the extreme ends of the latter for the purpose of eliminating splitting action along 110 the side edges.

3. A door for the purpose set forth consisting of a metal frame presenting radial corner projections projecting beyond the remaining metal component of the door; spaced transverse bracing means connecting the vertical members; hangers rigidly secured to the top corner radial projections in alignment with the side frame members and having their lower edges rigidly secured along the frame and extending from the inside thereof outwardly; and metal body members producing a door area overlapping the said corner projections to the extreme 120 ends of the latter for the purpose of elimi- 130

nating splitting action along the side edges.

4. The combination with an angle iron door frame having radial corner projections consisting of bent ends of the side and end frame members rigidly secured together; of angle iron fillers secured to the radial projections and presenting flat faces, hangers consisting of front and back members rigidly secured to the radial projections and presenting overlapping ends, and a trolley,

trolley frame and hanger-bolt united together in operative relation, with the hanger-bolt engaging the said overlapping ends.

In testimony whereof I have signed my name to this specification in the presence of 15 two witnesses.

JOHN WILSON ORROCK.
